UNITED STATES PATENT OFFICE.

EMIL SCHNURRENBERGER, OF PATERSON, NEW JERSEY.

DYEING-MACHINE.

1,350,740.

Specification of Letters Patent. Patented Aug. 24, 1920.

Application filed January 9, 1920. Serial No. 350,273.

To all whom it may concern:

Be it known that I, EMIL SCHNURRENBERGER, a citizen of the United States, residing at Paterson, in the county of Passaic 5 and State of New Jersey, have invented certain new and useful Improvements in Dyeing-Machines, of which the following is a specification.

In treating skeins with liquids, notably in 10 dyeing, the hand operation consists in shifting the sticks on which the skeins are hung and which rest on the sides of the liquor vat one after another along the vat so as to sweep the skeins through the liquor, thus 15 both to cause the skeins to be well permeated by the liquor and keep the latter well mixed; when this shifting has been done several times, first one way and then the other, the operators change the skeins so as to immerse 20 the part of each which was last exposed or out of the liquor. This manual operation is a slow, tedious and expensive one, and the object of the invention is therefore to provide a machine for accomplishing this work 25 in which these objections will be overcome, and while the principal object of attaining an effective sweep of each skein through the liquor will be accomplished, with consequent good permeation thereof by and an effective 30 stirring of the liquor of treatment, the skeins will be saved any injurious frictional contact with parts of the apparatus or with each other, which is a fault characterizing machines heretofore devised for doing this 35 work.

In the drawings,

Figure 1 is a side elevation, partly broken away, of the apparatus;

Fig. 2 is a plan;

Fig. 3 is an end elevation, the vats appearing in section;

Fig. 4 is a plan of the means for causing the sweep of the skeins through the liquor, with the main frame which supports it 45 shown in horizontal section;

Fig. 5 is a sectional detail of said means; and

Figs. 6, 7 and 8 are views illustrating three different positions of a skein.

In the present instance there are two vats 50 *a* shown, the means for supporting and moving the skeins being set between and arranged to overhang them.

A hydraulic ram *b* is shown with its upper 55 or moving member *b'* capped by a plate *c* which supports a horizontal frame compris-

ing the horizontal rails *d* and the cross-pieces *e*. The ram is adapted for raising and lowering the frame and the mechanism carried thereby when a treatment has been 60 effected and the treated skeins are to be removed and replaced by those to be treated. In transverse bearings *f* on this frame are journaled cross-shafts *g* each having a worm-and-worm-wheel connection *h* with a 65 longitudinal shaft *i* journaled in the cross-piece *e* of the frame, which shaft *i* has a gear *j* to mesh with a suitably driven gear *k* when the frame is lowered to position for a treatment of the skeins (Fig. 1). On the ends 70 of the shafts *g* are secured, as by set screws *l*, the socketed ends of the skein carrying reels *m*. The gear-connections *h* are preferably such that adjoining reels rotate reversely to each other, though this is not indispensable. 75

On the frame *d*—*e* is arranged to slide another frame including the longitudinal rails *n* and cross-pieces *o*; in the preferred construction the rails *d* have horizontal slots *d'* in which the cross-pieces of frame *n*—*o* slide 80 and are guided. For reciprocating the frame *n*—*o* there is a shaft *p* journaled in frame *d*—*e* and carrying a worm-wheel *q* in mesh with the worm of one of the gear-connections *h* and also a gear wheel *r* which 85 meshes with a pinion *s* on a shaft *t* journaled in frame *d*—*e* and carrying a crank disk *u* which is connected with the frame *n*—*o* by the pitman *v*.

Projecting laterally from rails *n* of frame 90 *n*—*o* are arms *o'* which carry rails *w*, and projecting from these rails are sticks arranged in two sets *x* *y*, each stick *x* being adapted to extend through a skein and each stick *y* to project between two adjoining 95 skeins. It will be better to form each rail *w* in two horizontally separate sections hinged together and mount one set of the sticks on the lower or fixed section and the other on the hinged section. In the present instance when the frame *n*—*o* is in its mid-position the lower row of sticks register vertically with the respective reels *m*, which are arranged at equal intervals, and the upper row register with the spaces between 100 the reels; the traverse of the frame may have any desired extent, in the present instance being somewhat more than the center-to-center spacing of the reels.

It will be understood that when the skeins 110 are being treated the rotation of shaft *i* transmits rotation, through gearing *h*, to

the several shafts g and hence to the reels, so as to cause movement of each skein on its reel after the manner of a belt on a pulley, thus to progressively immerse it in the liquor; and that at the same time frame $n-o$ is being reciprocated so that the sticks x, y , effect a sweeping of the skeins through the liquor first all one way and then all the other way, whereby the liquor is not only 5 kept stirred but is made to thoroughly and uniformly permeate the strands of the skeins. By arranging sticks x to penetrate the skeins each stretch or side of a skein is kept away from the opposite stretch or side, so 10 that they do not become matted together and uniformity of the treatment is thus promoted; the sticks y , which alternate with the skeins, serve to shift the relatively rearward stretch of each skein forward (in the 15 direction in which the sticks x are displacing the relatively forward stretches of the skeins) so that it will not be interfered with by the skein next behind.

In a well-known machine for performing 20 this work the skeins are hung on reels arranged eccentrically of horizontally rotating members, in which case if the speed of rotation is fast enough to obtain adequate stirring of the liquor and good permeation of 25 the skeins as they are swept through the same the skeins become unduly worn by the friction of the reels (particularly at their end heads or flanges) therewith. In my construction the rotary movement of the 30 reels and the sweeping movement of the skeins are not interdependent, because their speed ratio may be changed by changing the gearing connecting the rotary reel and the reciprocating frame $n-o$, and so the 35 rotary movement of the reels may be as slow as is expedient and the sweeping movement of the skeins as fast as necessary in order on the one hand to progressively subject each skein to the liquor without undue frictional wear by the reel and on the other to 40 insure good agitation of the liquor and thorough permeation of the skeins.

When the machine is unloaded and reloaded, at which time the ram has been 45 made to lift the skeins clear of the liquor, the frame $n-o$ will usually be first set at the mid-position of its traverse, so as to bring the sticks x in the most convenient relation to the reels, and at that time the 50 rail carrying the sticks y may be swung up on its hinges so as to be out of the way and avoid any possibility of some of the skeins being slipped over the sticks y .

The sweeping of the skeins through the 55 liquor of treatment is accomplished according to my invention so that the lower or immersed parts of the pendent skeins are trailed through the liquor by the displacing devices x, y , which so far as I am aware is 60 new in machines of this class; inasmuch as

by this manner of moving the skeins through the liquor they are left entirely free for individual movement there results in all cases that uniformity of treatment which has heretofore only characterized the manual operation already described.

Having thus fully described my invention, what I claim and desire to secure by Letters Patent is:

1. In a machine for treating skeins with 75 liquids, the combination, with a vat for the liquor of treatment, of means to support a skein pendent in and to cause the skein to trail through the liquor including a skein-trailing member movable laterally in substantially a plane, and means to move said member in said plane.

2. In a machine for treating skeins with 80 liquids, the combination, with a vat for the liquor of treatment, of means to support a skein pendent in and to cause the skein to trail through the liquor including a skein-trailing member movable laterally in substantially a plane, and means to reciprocate 85 said member in said plane.

3. In a machine for treating skeins with 90 liquids, the combination, with a vat for the liquor of treatment, of means to support a skein pendent in the liquor, and means to cause the pendent part of the skein to trail 95 through the liquor including a skein-displacing member movable independently of and laterally relatively to the first means and engageable with the skein at a point above the lower end thereof.

4. In a machine for treating skeins with 100 liquids, the combination, with a vat for the liquor of treatment, of means to support an endless skein pendent in the liquor, and means to cause the pendent part of the skein 105 to trail through the liquor including a skein-displacing member penetrating the skein at a point above the lower end thereof and movable independently of and laterally relatively to the first means.

5. In a machine for treating skeins with 110 liquids, the combination, with a vat for the liquor of treatment, of means to support an endless skein pendent in the liquor, and means to displace the pendent part of the skein laterally in the liquor movable laterally and having two skein-displacing portions, one penetrating the skein and the other arranged rearward thereof relatively 115 to the direction of movement of said means.

6. In a machine for treating skeins with 120 liquids, the combination, with a vat for the liquor of treatment, of means to support the skeins pendent in and cause the skeins to trail through the liquor including a unitary skein-trailing structure movable laterally and having skein-engaging portions arranged one after another lengthwise of the path of movement of said structure.

7. In a machine for treating skeins with 125

- liquids, the combination, with a vat for the liquor of treatment, of means to support the skeins pendent in the liquor and in a series side by side, and a series of devices, movable 5 independently of the first means and against the pendent portions of the respective skeins, for trailing said skeins through the liquor.
8. In a machine for treating skeins with liquids, the combination, with a vat for the liquor of treatment, of means to support the skeins pendent in the liquor and in a series side by side, of a frame movable longitudinally of the series of skeins and skein-displacing devices on the frame extending 10 transversely of the skeins and the path of movement of said frame and arranged to respectively engage the pendent portions of the skeins.
9. In a machine for treating skeins with liquids, the combination, with a vat for the liquor of treatment, of a rotary support on which to hang pendent in the liquor an endless skein penetrated thereby, and a skein-displacing member arranged below the support and movable laterally with reference 15 to said support.
10. In a machine for treating skeins with liquids the combination, with a vat for the liquor of treatment, of a rotary support on which to hang pendent in the liquor an endless skein penetrated thereby, a skein-displacing member arranged below the support and movable laterally with reference 20 to said support.
11. In a machine for treating skeins with liquids the combination, with a vat for the liquor of treatment, of skein supporting means including spaced elongated substantially horizontal skein supports on which to 25 hang the skeins pendent, and skein-displacing means including a supporting structure and a series of spaced elongated substantially horizontal skein-displacing devices arranged to alternate with said supports, one 30 of said means being movable relatively to the other lengthwise of said series and the latter being movable in said structure on a horizontal axis.
12. In a machine for treating skeins with liquids, the combination, with a vat for the liquor of treatment, of means to support the skeins pendent and spaced from each other, and skein-displacing means including two 35 series of spaced elongated substantially horizontal skein-displacing devices arranged to alternate with each other and one series being adapted to penetrate the respective skeins and the other to alternate with the skeins, one of said means being movable 40 relatively to the other lengthwise of said series and one of said series being movable on a horizontal axis relatively to the other series.

In testimony whereof I affix my signature.
EMIL SCHNURRENBERGER.
